UNITED STATES PATENT OFFICE.

WILLIAM EDWARDS, OF GLENDIVE, MONTANA TERRITORY.

IMPLEMENT FOR CLEANING MACHINERY.

SPECIFICATION forming part of Letters Patent No. 323,502, dated August 4, 1885.

Application filed January 5, 1885. (No model.)

To all whom it may concern:

Be it known that I, WILLIAM EDWARDS, a citizen of the United States, residing at Glendive, in the county of Dawson and Territory 5 of Montana, have invented certain new and useful Improvements in Implements for Cleaning Machinery; and I do hereby declare that the following is a full, clear, and exact description of the same, reference being had to the annexed drawings, making a part of this specification, and to the letters and figures of reference marked thereon.

Figure 1 of the drawings is a perspective view of my improved implement; Fig. 2, a 15 detail view in perspective of that portion of the implement used as a cleaner, and Fig. 3 a similar view of the scraper.

The object of the present invention is to provide a simple and practical implement that 20 can be conveniently used to clean the eccentrics, cross-heads, guides, feed-pipes, links, driving boxes and wheels, and other parts of a locomotive or other engine; and it consists in the general construction of the implement, 25 substantially as shown in the drawings, and hereinafter described and claimed.

In the accompanying drawings, A represents the cleaner, and B the scraper, and when connected together the cleaner forms the 30 handle of the implement, as shown in Fig. 1.

The cleaner and scraper are formed of any suitable metal, but preferably of steel, the cleaner A being of any desirable length and width.

35 The scraper B is formed with a flange, a, along its outer edge for scraping the driving-wheels and other parts of the engine. The side edges of the scraper are formed with arches b c, which are different in size, to fit 40 over the convex surface of the feed-pipes, rods, and other portions of an engine of like form, where a flat or straight edge scraper could not be successfully brought into use.

In order to provide means for conveniently 45 attaching the cleaner A to the scraper B, the latter is preferably formed with two elongated slots, d, of a length equal to the width of the cleaner, said cleaner being inserted or passed through the slots, as shown in Fig. 1, thus 50 forming the handle to the scraper.

The curved end e of the cleaner A prevents the scraper from becoming accidentally detached, and when the straight edge f of the scraper is required for use the scraper is simply reversed, so as to bring the straight edge 55 to the outer end of the cleaner A.

Every provision is made in the construction of the scraper B to clean the exterior surface of almost any portion of an engine, and, if preferred, a series of arches of varying sizes 60 may be made on each of the side edges of the scraper in order to adapt it to different size rods and pipes; or the arches may be made very shallow, which will attain the same object.

65 The curved end e of the cleaner A, although serving the purpose of preventing the scraper B from becoming detached, its especial and important object is to adapt it for use in cleaning the driving boxes and wedges of the engine where the scraper could not be used owing to its size and shape.

70 The means employed for attaching the cleaner A and scraper B together is not considered material, as any other means may be substituted which comes within ordinary mechanical skill without departing from the principle of my invention.

75 The cleaner A is bifurcated at its end, as shown at g, to receive and hold the "waste," 80 consisting of the refuse of cotton and wool, used as swabs for wiping machinery. The waste, after being taken up by the bifurcated end g from the main bulk of waste, is wrapped around the notched portion h, which holds it 85 in place sufficiently to force it between the eccentrics and other parts of the engine.

80 The above-described implement is equally applicable to all classes of machinery, and can be used on stationary as well as locomotive 90 engines.

Having now fully described my invention, what I claim as new, and desire to secure by Letters Patent, is—

95 1. An implement for cleaning machinery, consisting of a flat metal plate or bar bifurcated and notched at one end, and having detachably connected at its opposite end a scraper, substantially as and for the purpose set forth.

2. An implement for cleaning machinery, consisting of a metal plate or bar having at one end a bifurcation and notch, substantially as and for the purpose described.
- 5 3. An implement for cleaning machinery, consisting of a metal plate or bar bifurcated and notched at one end and curved at the other, substantially as and for the purpose described.

In testimony that I claim the above I have to hereunto subscribed my name in the presence of two witnesses.

WILLIAM EDWARDS.
